(57) **CLAIM**

(22) Filed: **Jun. 1, 2006**

The ornamental design for a tread portion of an automobile tire, as shown and described.

(30) **Foreign Application Priority Data**

Dec. 1, 2005 (JP) 2005-035549

DESCRIPTION

(51) **LOC (8) Cl.** **12-15**

FIG. 1 is a perspective view of an automobile tire, it being understood that the tread pattern repeats uniformly throughout the circumference of the tire.

(52) **U.S. Cl.** **D12/588**

FIG. 2 is a front elevation view thereof. A top plan view, a bottom plan view, and a rear elevation view are identical with the front elevation view.
